INSTANTANEOUS ELECTRIC WATER
HEATER

Louis Ludwig, Brooklyn, N. Y.

Application July 25, 1932, Serial No. 624,389

3 Claims. (Cl. 219—40)

The invention relates to the type of electric water heaters which are attached to a water faucet and which heats the water as it flows through the heater. The present invention has 5 for its main object to provide a heater which is completely automatic in its operation, in that it does not require any switch mechanism of any kind but is automatically switched on or off by the starting or the stopping of the flow of water 10 through it.

Another object is to provide a heater in which the heating element is to a large extent self cleaning, in that the flowing water removes and carries off any deposits which are ordinarily apt 15 to accumulate on the electrodes. A further object is to so construct the device that the heating element may be quickly and easily removed or installed. A still further object is to provide a heating element which will consume a minimum 20 amount of current and which will not burn out. Additional objects are to provide a heater which may readily be attached to any ordinary faucet which has no parts easily broken or apt to get out of order, which is light in weight, which is neat 25 and pleasing in appearance, which requires little space, and which is inexpensive to manufacture.

These and various other objects and advantages will be readily understood from the following description and from the accompanying drawing 30 ing of a preferred embodiment of the invention in which, however, modifications may be made without departing from the scope of the appended claims. In the drawing

Fig. 1 is a cross-sectional front view of the 35 heater.

Fig. 2 a cross-sectional side view,

Fig. 3 a top view,

Fig. 4 another top view with the cap removed, and

Fig. 5 an enlarged cross-sectional view of the 40 heating element showing its construction in detail.

Referring first to Figs. 1 to 4, the device comprises a housing 10, a cap 11 and a heating element 12. The housing is made of insulating material, while the cap is preferably made of metal. The housing is constructed with a large, downwardly extending chamber 13 in which the element 12 is suspended, and is provided, at its upper end, with two oppositely-disposed lugs 14 and 15 in which holes 16 and 17 are molded.

The cap is of the same configuration as the upper end of the housing and provided with an upwardly-extending and internally-threaded neck 55 18 in which a plurality of screws 19 is radially

mounted. The cap is secured to the housing by bolts 20 and 21 and a gasket 22 seals the joint between the cap and the housing. A resilient gasket 23 is also placed in the bottom of the threaded part of the neck 18. An opening 24, formed 60 through the gaskets 22 and 23 and the cap 11, leads from the neck 18 to the chamber 13.

Referring now also to Fig. 5, the heating element consists of a plurality of plates or electrodes which are clamped together by bolts 25 65 and 26. The plates are preferably made of monel metal, and the element is preferably assembled in the following manner. Alternate plates 27 are provided at one end with holes which fit tightly around the bolt 25 and at the opposite ends with 70 larger holes in which the shoulders of insulating collars 28 fit. These collars are mounted on the bolt 26. The other plates 29 are similarly provided at one end with holes fitting tightly around the bolt 26 and at the other ends with 75 holes fitting on the shoulders of insulating collars 30. Additional insulating washers 31 and 32 are inserted between the plates. Thus, every other plate is electrically connected to the bolt 25, while the alternate plates are electrically connected to the bolt 26 but insulated from the plates 80 connected to the bolt 25.

Two oppositely disposed recesses or seats 33 and 34 are molded in the top face of the housing. The heating element is suspended in the chamber 13 85 by having the ends of the bolt 25 supported in these seats, as plainly shown in Fig. 1. A groove 35 is also formed in the top face of the housing and in this groove a soft rubber bushing 36 is placed. A rubber covered electric cable 37 is 90 passed through this bushing and the conductors 38 and 39, contained in this cable, are connected, respectively, to the bolts 25 and 26. The bushing 26 and the cable 37 form a water tight seal in the groove 35 when the cap is clamped on the 95 housing. An outlet 40 extends downwardly from the upper part of the chamber 13.

The device operates in the following manner; the cap 11 is secured to a faucet and the cable 37 attached to a source of electric current. Until 100 the water is turned on no current can flow through the heating element owing to the alternate plates being insulated and separated from each other. When the water is turned on it will flow through the opening 24, run down between 105 the plates 27 and 29, fill the chamber 13 and flow out through the outlet 40. The water between the plates will act as a conductor and the high resistance of the water will cause it to become very hot. When the faucet is closed the water 110

left in the chamber will be vaporized until it sinks below the ends of the plates, after which the current will cease to flow, thus automatically switching off the heater.

- 6 In heating water between electrodes there is a tendency for the water to decompose into its gaseous elements. If the plates are placed horizontally, bubbles of these gases have a tendency to form on the under sides of the plates while sediments tend to form on the upper sides, thus fouling the plates and decreasing the areas of the active surfaces. In the present invention this is entirely overcome. The water as it is forced between the vertical plates removes both the gases and the sediment. It will also be noted that by suspending the heating element in the manner shown, it is a simple matter to remove this so that both it and the housing may be cleaned with great ease.
- 10 By providing the cap with the screws 19 in addition to the thread, it is possible to attach the device to any ordinary faucet regardless of the shape of its nozzle. The gasket 23 forms a water tight seal between the cap and the nozzle.
- 15 While I have mentioned that I prefer to employ plates made of Monel metal, I do not wish to limit the invention to the use of such metal only, nor do I wish to confine myself to employing the means shown and described for insulating the plates of the heating element from each other; as various other methods might be employed.

From the foregoing it will be seen that this device is thoroughly automatic in operation, practically self-cleaning, simple and inexpensive in construction, and that it may be readily attached to any ordinary faucet.

Having described my invention and its operation, what I claim as new and wish to protect by Letters Patent is:

- 40 1. In a water heater of the class described, an insulating housing having a downwardly extending chamber, a cap secured on said housing and having means for attaching it to a faucet, a water outlet leading from the upper part of the chamber, an electric heating element vertically suspended in said chamber and consisting of a set of vertical plates electrically connected with each other and another set of vertical plates alternately interposed between the first-mentioned plates and also electrically connected with each other, said last-mentioned plates spaced and insulated from the first-mentioned plates, the sets of plates

constituting the electrodes of the heating element, a rod extending through the upper end of the heating element, two oppositely-disposed seats formed in the upper face of the housing in which seats the ends of the rod rest, and means for connecting said heating element to a source of electric current. 80

2. In a water heater of the class described, an insulating housing having a downwardly extending chamber, a cap secured on said housing and having means for attaching it to a faucet, a water outlet leading from the upper part of the chamber, an electric heating element vertically suspended in said chamber and consisting of a set of vertical plates electrically connected with each other and another set of vertical plates alternately interposed between the first-mentioned plates and also electrically connected with each other, said last-mentioned plates spaced and insulated from the first-mentioned plates, the sets of plates constituting the electrodes of the heating element, a rod extending through the upper end of the heating element, two oppositely-disposed seats formed in the upper face of the housing in which seats the ends of the rod rest, electric conductors 90 for connecting said heating element to a source of electric current, and means for water-tightly sealing the opening through which said conductors pass. 95

3. In a water heater of the class described, an insulating housing having a downwardly extending chamber, a cap secured on said housing and provided with means for attaching it to a faucet, a water outlet leading from the chamber, an electric heating element vertically suspended in said chamber and consisting of a set of vertical plates electrically connected with each other and another set of vertical plates alternately interposed between the first mentioned plate and also electrically connected with each other, said last-mentioned plates spaced and insulated from the first-mentioned plates, the sets of plates constituting the electrodes of the heating element, all of said plates held together by an upper and a lower rod so as to form a self-contained unit, the rods forming the terminals of the heating element, the upper rod extended on both sides of the heating element to form a means by which the element may be suspended in the chamber, and means for connecting the rods to a source of electric current. 110 115 120 125
